(57) **CLAIM**

The ornamental design for a package sleeve, as shown and described.

DESCRIPTION

FIG. 1 is a perspective view of the package sleeve according to an embodiment of the present invention;

FIG. 2 is a front view of the package sleeve shown in FIG. 1; FIG. 3 is a back view of the package sleeve shown in FIG. 1; FIG. 4 is a left side view of the package sleeve shown in FIG. 1;

FIG. 5 is a right side view of the package sleeve shown in FIG. 1;

FIG. 6 is a top view of the package sleeve shown in FIG. 1; and,

FIG. 7 is a bottom view of the package sleeve shown in FIG. 1.

In the drawings, the dot-dash lines represent the boundaries of the claim. The broken lines are for the purpose of illustrating environment only and form no part of the claimed design.
